Darell Boyd Harmon, Austin, Tex., assignor to
American Seating Company, Grand Rapids,
Mich., a corporation of New Jersey

Application January 14, 1952, Serial No. 18,048

Term of patent 14 years

(Cl. D33—7)

To all whom it may concern:

Be it known that I, Darell Boyd Harmon, a citizen of the United States, residing at Austin, in the county of Travis and State of Texas, have invented a new, original, and ornamental Design for a Double Desk Unit, of which the following is a specification, reference being had to the accompanying drawing, forming a part thereof.

Figure 1 is a front perspective view of a double desk unit, showing my new design; and Figure 2 is a rear perspective view of the same.

I claim:

The ornamental design for a double desk unit, substantially as shown.

DARELL BOYD HARMON.
